METALLIC RING GUARD OR THE LIKE

Benita Livingston, Highland Park, Ill.
Application January 9, 1958, Serial No. 49,183

Term of patent 14 years
(Cl. D45—10)

Fig. 1.

Fig. 2.

Fig. 3.

Fig. 1 is a side elevational view of a metallic ring guard or the like showing my new design which includes the brushed surface ornamentation shown therein;

Fig. 2 is a top plan view thereof; and

Fig. 3 is an end elevational view thereof.

The design comprises a tapered, open metallic ring or the like which is widest at the open end thereof and bears a slot adapted to receive a jeweled finger ring, the entire surface of the guard having a brushed appearance as shown.

The broken line showing of a diamond ring is for illustrative purposes only.

I claim:

The ornamental design for a metallic ring guard or the like, as shown and described.
